UNITED STATES PATENT OFFICE.

WILLIAM H. GOLDSMITH, JR., OF BIDDEFORD, MAINE, ASSIGNOR TO SACO-LOWELL SHOPS, OF BOSTON, MASSACHUSETTS, A CORPORATION OF MASSACHUSETTS.

BUILDER-MOTION.

1,136,417.

Specification of Letters Patent. Patented Apr. 26, 1915.

Application filed May 22, 1914. Serial No. 840,273.

To all whom it may concern:

Be it known that I, WILLIAM H. GOLDSMITH, Jr., of Biddeford, in the county of York and State of Maine, a citizen of the 5 United States, have invented a new and useful Improvement in Builder-Motions, of which the following is a full, clear, and exact description, reference being had to the accompanying drawings, forming a part of 10 this specification, in explaining its nature.

My invention relates to a builder motion adapted to make either a "filling" wind or a "warp" wind.

The essential object of my invention is to 15 provide a builder motion capable of considerable variation in the production of a filling wind for varying the character of such wind, and which builder can easily be converted into one for making a warp wind.

20 The invention can best be seen by reference to the drawings in which an embodiment thereof is shown and such portion of a spinning frame as is incidentally used for supporting various parts of the builder.

25 Figure 1 shows the builder in side elevation. Fig. 2 is a section on the line 2—2 of Fig. 1. Fig. 3 is a section on the line 3—3 of Fig. 1. Fig. 4 is a forward end elevation of the builder, other parts to which reference 30 will hereinafter be made being shown in side elevation. Fig. 5 is a front elevation of a detail of construction to which special reference will hereinafter be made. Figs. 35 6, 7, 8 and 9 are diagrammatic side elevations of the builder showing certain variations obtained in the operation thereof for varying the character of the wind as will later be more fully explained. Figs. 10 and 40 11 are side elevations of the builder when altered to make a warp wind.

Referring to the drawings:—1 represents the builder arm; 2 the stud on which the arm is pivotally mounted and which has any suitable fixture or base of support as a frame. 45 3 which corresponds with the end of a spinning frame. The builder arm is overweighted by a weight 4 on the end thereof.

Arranged upon the rear side of the builder arm is a cam roll 5 (see Fig. 2) 50 engaging which is a cam 6 for rocking the arm. This cam is supported and operated

in any suitable manner. In the drawing the cam is shown pivotally mounted upon a stud 7 secured to the frame 3. Above the builder arm is arranged a pulley 8 pivotally mounted to turn within a carrier 9. This carrier is arranged to turn within a suitable bracket 10 upon an axis 11 at substantially right angles to the longitudinal line of the builder arm. In other words, the pulley 8 not only turns within this carrier, but is also arranged to turn about the axis 11. The bracket 10 is secured to the frame 3 or may be otherwise suitably supported. Extending over and around the pulley 8 is a chain 12 which extends to connect with a rocking segment 13 (see Fig. 4) for controlling the side rails of the spinning frame in the usual manner. The inner end of the chain 12 and portions adjacent thereto connect with the 70 builder arm as follows: Carried by the builder arm is a curved rack 15. This rack has a curvature normally concentric with the axis 11 above referred to and is mounted within a frame 16 carried by the builder 75 arm, the arrangement of the parts being such that the rack may have either a forward or reverse endwise movement around the axis 11. The rack is held against lateral and edgewise displacement by the inner 80 side or face of the frame against which it bears, while the top and bottom edges of the rack are confined by flanges 17 and 18, respectively, which form guides for the rack.

Pivotedly secured to the rack at a point 85 adjacent the inner end thereof, or that nearest the fulcrum of the builder arm, is a pulley or sheave 19 around which the chain 12 is passed from the pulley 8. Secured also to the rack just forward 90 of the sheave 19 is a segment 20. The curvature of this segment is such that the bottom edge 21 thereof may normally present an arc concentric with the path of the rack and practically flush with the bottom 95 peripheral edge of the sheave 19 so that the chain 12 after passing over the sheave 19 may thence extend outwardly beneath the edge 21 of the segment to bear against this edge. The segment 20 is secured to the rack 100 by screws 22, the heads of the screws being preferably countersunk. The inner end of

the chain 12 is releasably secured in any suitable manner to a fixture or holder 23 secured to the forward end of the builder arm.

While the segment 20 is described as being fixedly secured to the rack and also as presenting a bottom edge concentric with the path of the rack, provision is made whereby the bottom edge of the segment against which the chain bears may occupy a position eccentric with relation to the path of the rack. For obtaining this effect the segment is adjutably secured to the rack, provision being made for such adjustment by slots 24 formed in the segment through which the screws 22 extend. These slots 24 are concentric with the sheave 19 in order that the bottom edge 21 of the segment may always be flush with the bottom peripheral edge of the sheave, whatever the adjusted position of the segment may be. Provision is also made whereby the end of the chain which connects with the holder may also have a variable point of fixture with relation to the axis of the sheave 19 around which the chain is passed. This effect is obtained by the formation of a relatively long vertical slot 25 in the holder, the retention of the chain being effected at any point in the holder within the extension of this slot.

The rack 15 is moved by means of a worm 27 on a shaft 28 journaled to turn within the builder arm. For operating this shaft there is arranged upon the outer end thereof of a ratchet wheel 29. This wheel has a hub 30 through which passes a set screw 31 for fixing the wheel to the shaft. In conjunction with this wheel is an overweighted pawl 32 pivotally secured to the builder arm. Cooperating with the pawl 32 is a finger 33 adjustably mounted on a bracket 34 having any suitable fixture of support, as for example, the under side of the side bar 35 of the spinning frame, a portion of which is shown. The coördination and consequent operation of these parts last described for effecting the rotation of the shaft 28 and movement of the rack 27 need no special description as they are well known to those skilled in the art.

The mechanism above described is that especially adapted for making a "filling" wind or that in which the ring rail has a normal relatively slight "traverse" or reciprocatory movement with relation to the bobbin and also a gradual increase in elevation with relation thereto, which will hereinafter be referred to as "gain". The extent of "traverse" depends upon the extent of rocking motion imparted to the arm of the builder and, also, upon the point where the chain leaves the builder arm with relation to its point of fulcrumage. In other words, the traverse depends upon the

position occupied by the sheave 19, the traverse becoming gradually increased as this sheave is moved outwardly along the longitudinal line of the builder arm away from its point of fulcrumage, or diminished as the sheave is moved in a reverse direction.

The "gain" depends upon the letting out of the chain 12, the extent of gain during any interval depending upon the amount the chain is let out during such interval. For making a "filling" wind the usual practice is to start with a short traverse and gradually increase the length of the traverse to the end of the wind. The gain, however, is largely a matter of choice, a constant or normal gain being preferred in some instances; a variable gain in others. Referring now to this device in the light of these considerations, the operation is as follows: The rack 15 is first moved inwardly in the direction of the fulcrum of the builder arm to a position where the sheave 19 will occupy such near relative position to the fulcrum of the builder arm as to obtain the desired initial short traverse. Assuming now the motion to be set in operation, the rocking movement of the builder arm tends to bring the pawl 32 in contact with the finger 33 which tends to actuate the ratchet wheel 29 turning the shaft 28 and worm 27 thereon and moving the rack 15 outwardly upon the builder arm, thereby causing a continuing outward displacement of the sheave 19 carried by the rack and accordingly increasing the extent of "traverse". The movement of the rack and sheave 19 and consequent increase of "traverse" is very slight for each reciprocation of the builder arm and depends upon the extent of movement imparted to the ratchet wheel, this depending upon the graduated or adjusted position of the finger 33 which is engaged by the pawl for actuating the ratchet wheel. The increase in "traverse" is substantially a normal increase although owing to the curvature of the rack the sheave 19 will tend to move faster along the longitudinal line of the rack as the movement of the sheave approaches a line parallel therewith, the tendency of the construction accordingly being that the sheave 19 will be moved slightly faster during a prescribed interval as approach is made to the end of the wind, the sheave then having been moved to a position where its outward movement is in a line substantially parallel with the longitudinal line of the builder arm.

In the present device the letting out of the chain 12 and resulting gain will depend upon a variety of considerations including the relative outward movement of the sheave 19 along the line of the builder arm toward the fixture or holder 23 to which

the end of the chain is secured; upon the angle made by the portions of the chain which render on to and off the sheave 19; upon the distance separating the sheave 5 from the pulley 8 during the movement of the sheave, and also upon the path of the sheave with relation to the lay of the chain between the sheave and the holder to which the end of the chain is secured.

10 Referring first to Fig. 6 in which the segment 20 is eliminated and the chain extends in a direct line from the sheave 19 to the holder to which the end of the chain is secured: As the sheave moves outwardly upon 15 the builder arm, increasing the traverse as aforesaid, it will follow a path about the axis 11. Therefore the portion of the chain extending between the sheave 19 and pulley 8 will remain constant. As the sheave progresses outwardly, however, the angle formed between the portion of the chain rendering onto and off the sheave 19 becomes gradually less acute, thereby tending to let out less chain. At the same time the 25 direction or path of the sheave 19 becomes more direct to that point of the holder at which the end of the chain is secured with a tendency to let out a gradually increasing amount of chain, the resultant action being such as to impart a relatively slow gain substantially constant throughout, though tending to increase slightly. This gain in practice has been found very satisfactory and may be considerably varied by the adjustment 30 of the end of the chain in the holder.

Assuming now that the segment 20 is used and is placed in a normally adjusted position as shown in Fig. 1, or a position where that curved portion of the chain bearing 40 against the under edge thereof will lie in a position concentric with the path of the rack; in other words, lie in the path described by the sheave 19: Under these circumstances there is obtained an exact normal gain throughout, though somewhat faster than that above described. The reason why the gain is a normal gain is because the conditions remain normal throughout the movement of the builder. Assuming 45 now that the segment is moved to an eccentric adjusted position (with relation to the axis 11) as shown in Fig. 7: Under these circumstances a further variance in gain is effected, the gain being a substantially normal gain though slower than when the segment is occupying its normal position as shown in Fig. 1. Assuming that the segment is adjusted to an eccentric position (to the axis 11) as indicated in Fig. 8: Under 50 these circumstances there is obtained a substantially constant gain though one faster than that obtained when the chain is occupying its normal position as shown in Fig. 1.

Other variations may be obtained depend-

ing upon the further adjusted position of 65 the segment and also upon the adjusted position of the end of the chain in the holder; as for example, upon the point where the chain tangentially leaves the segment as illustrated in Fig. 9. That is, the device 70 shown is one capable of effecting a considerable variety in gain, and enables one to obtain that gain which he considers to be most advantageous for his particular purpose.

In Figs. 10 and 11 the aforescribed 75 builder is shown converted into one for making a "warp" wind, slight changes only being necessary and these as follows: The cam 6 is replaced by a warp-winding cam 40. The chain 12 is fastened by a hook 41 80 directly to a stud 42 on the segment 20 which is set in a normal position as shown in Fig. 1. In case the segment is not used then the stud 42 may be secured directly to the side of the rack 15 as shown in Fig. 11. The ratchet wheel 29 is reversed on the shaft 28 or another wheel substituted in which the teeth are reverse to those on ratchet wheel 29 as shown in Fig. 1. The changed position of the ratchet wheel is shown in Fig. 5. 85 In conjunction with the wheel as changed is an overweighted pawl 43 pivotally secured to the builder arm and adapted to engage a finger 44. This finger is secured to a bracket 45 adjustably mounted on the frame 3 whereby the position of the finger 44 may be varied and the pawl 43 strike the same at different adjusted positions of the finger for 90 rotating the ratchet wheel and shaft 28 in the usual manner as the builder arm is reciprocated.

The operation is as follows: The rack is first set in a position substantially as shown in Figs. 10 and 11, or in such position as will give the proper initial "traverse" to the ring rail. As the builder arm is reciprocated the rack will be gradually moved inwardly by the intermittent rotation of the shaft 28 through the operation of the ratchet wheel and connecting mechanism. The 105 effect is to gradually lessen the extent of traverse as is customary in this kind of wind because the stud 42 with which the chain connects becomes gradually moved nearer to the fulcrum of the builder arm. During 110 this operation there will be no letting out of the chain before characterized as "gain" owing to the fact that the stud 42 remains at all times in the direct path of the rack or segment and at the same normal distance 115 from the axis 11.

It is obvious that the mechanism heretofore described may be changed without departing from the spirit of my invention especially with relation to a variance in the 125 mechanism for obtaining the "filling" wind as first described, for varying the character of such wind.

Having thus fully described my invention, I claim and desire to secure by Letters Patent of the United States:—

1. In a builder motion, a builder arm, a fulcrum of support for said arm, a curved rack mounted upon said arm and movable thereon, a chain, a member carried by said rack and around which said chain loosely passes to extend outwardly along said arm and connect therewith, means for effecting such connection, and automatic means for moving said rack outwardly on said arm during the reciprocation thereof.
2. In a builder motion, the combination with a pulley and pivoted support therefor, of a builder arm arranged below said pulley and support, means for reciprocating said arm, a curved rack mounted upon said arm and movable thereon, said rack having a curvature and path of motion concentric with the axis of said support, a chain extending downwardly from said pulley, a member carried by said rack and around which said chain loosely passes to extend outwardly therefrom along said arm and connecting therewith, means for effecting such connection, and automatic means for moving said rack outwardly on said arm during the reciprocation thereof.
3. In a builder motion, a builder arm, means for reciprocating said arm, a curved rack mounted upon said arm and movable thereon, a chain, a member carried by said rack around which said chain loosely passes to extend outwardly therefrom and connecting with said arm, means forming such connection, means whereby the line of the chain between said member and its connection with said arm may be varied, and automatic means for moving said rack outwardly on said arm during reciprocation thereof.
4. In a builder motion, a builder arm, means for reciprocating said arm, a curved rack mounted upon said arm and movable thereon, a chain, a member carried by said rack around which said chain loosely passes to extend outwardly therefrom and connecting with said arm, means forming such connection, means whereby the lay of the chain may be varied between said member and point where said chain connects with said arm, and automatic means for moving said rack outwardly on said arm during the reciprocation thereof.
5. In a builder motion, a builder arm, a fulcrum of support therefor, means for reciprocating said arm, a curved rack mounted upon said arm and movable in a curved path thereon, a chain, a member carried by said rack around which said chain loosely passes to extend outwardly therefrom and connecting with said arm, means for effecting such connection, means whereby the lay of the chain between said member and its

point of connection with said arm may be varied with relation to a center around which said rack moves during the movement thereof on said arm, and automatic means for moving said rack outwardly on said arm during the reciprocation thereof.

6. In a builder motion, a builder arm, a fulcrum of support therefor, means for reciprocating said arm, a curved rack mounted upon said arm and movable thereon, a chain connecting with said arm, a segment carried by said rack and beneath which said chain extends, said segment defining the lay of the extended portion of said chain, and automatic means for moving said rack outwardly on said arm during the reciprocation thereof.

7. In a builder motion, a builder arm, a fulcrum of support therefor, means for reciprocating said arm, a curved rack mounted upon said arm and movable outwardly thereon in a curved path, a segment carried by said rack and presenting an edge concentric with a center of the path of said rack, a chain extending outwardly beneath said segment and bearing against said edge, said chain connecting with said arm, means forming such connection, and automatic means for moving said rack outwardly on said arm during the reciprocation thereof.

8. In a builder motion, a builder arm, a fulcrum of support therefor, means for reciprocating said arm, a curved rack mounted upon said arm and movable outwardly thereon in a curved path, a segment carried by said rack and presenting a curved edge, means whereby said segment and edge presented thereby may be varied with relation to the path of said rack, a chain extending beneath the edge of said segment to bear against the same and connecting with said arm, means for effecting such connection, and automatic means for moving said rack outwardly on said arm during the reciprocation thereof.

9. In a builder motion, a builder arm, a fulcrum of support therefor, means for reciprocating said arm, a curved rack mounted upon said arm and movable in a curved path thereon, a chain, a member carried by said rack around which said chain loosely passes to extend outwardly therefrom, a fixture connecting with said arm and with which the end of said chain connects, means for adjustably securing the end of said chain to said fixture whereby it may be set in different adjusted positions with relation to the longitudinal line of said arm, and automatic means for moving said rack outwardly on said arm during the reciprocation thereof.

10. In a builder motion, a builder arm, a fulcrum of support therefor, means for reciprocating said arm, a curved rack mount-

ed upon said arm and movable thereon in a curved path, a pulley carried by said rack, a segment presenting a curved edge also carried by said rack, a chain passed around 5 said pulley, thence extending outwardly beneath the edge of said segment to bear against the same, a fixture carried by said arm to which the end of said chain is se- cured, and automatic means for moving said rack outwardly on said arm during the re- 10 ciprocation thereof.
